UNITED STATES PATENT OFFICE

ALFRED S. CATAUDELLA, OF BRIDGEPORT, CONNECTICUT
BRAKE BAND SIGNALING DEVICE

Application filed February 5, 1931. Serial No. 513,509.

This invention relates to new and useful improvements in automobile brakes and more particularly to means for automatically signaling the driver when the brake bands begin to come worn through, so that the operator will know instantly that the lining is worn out and a new one is required, thus avoiding the possibility of a driver operating a car unknowingly, with defective brakes.

10 I find that it is often the case, in the use of automobiles, that brakes are frequently used and relied upon after the bands have been worn through, but unknown to the operator, until an emergency arises when the 15 brakes are applied and fail to take hold. Therefore, the importance of the improved signaling device, as above suggested, that serves to indicate to the driver the fact that the brake lining has worn through and can 20 be no further depended upon.

This signaling device briefly includes a copper strip, insulated, positioned beneath the lining and intermediate of it and the shoe, and an electric wire connection, a battery, a 25 lamp or bell, the latter of which can be located upon the dash board, so that a circuit is made or broken by the wearing of a hole through the brake band.

Other objects and advantages will become 30 apparent from a consideration of the following detailed description taken in connection with the accompanying drawing wherein one satisfactory embodiment of the invention is shown. However, it is to be understood that 35 the description and drawing are for the purpose of making clear the construction and operation of the principles of the invention and are not to be considered a limiting of its scope since changes in construction, combination and arrangement of parts may well be 40 made within the scope of the appended claims to which reference must be had for a definition of the limitations of the invention.

Upon the accompanying drawing forming 45 a part of this specification the same characters

of reference will be found to denote like or corresponding parts throughout the several figures, and of which:

Fig. 1 shows a front elevation of a fixed or shell member of a modern type of automobile brake having my improved signaling device applied thereto;

Fig. 2 is an enlarged, horizontal cross section, taken on line 2-2 of Fig. 1, through the said fixed member and a rotatable wheel 55 and drum mounted thereon;

Fig. 3 shows a similar enlarged, sectional side elevational view of a portion of the brake shell shown in Fig. 1, taken on line 3-3 of Fig. 2;

Fig. 4 shows a detached plan view of the insulated copper strip secured between the brake shoe and brake lining and having an electric circuit wire attached thereto; and

Fig. 5 shows a longitudinal section through 65 the insulated copper strip and insulative covering shown in Fig. 4.

Referring in detail to the characters of reference marked upon the drawing, 10 represents a portion of a disk wheel, and 11 the 70 cylindrical brake drum forming an integral part of the wheel and adapted to be rotated therewith, and which may be of the usual or any preferred construction. 12 represents a 75 fixed brake shoe member having a stamped-up recessed portion 13 in which is provided a central hole 14 to accommodate an axle 15 and axle housing 16, and is further provided with screw holes 17 whereby the shell may be 80 secured to the end of the axle housing and thus form a fixed member of the brake with respect to which the before mentioned wheel and drum rotate.

One end portion of each of a pair of semi-circular shaped shoes 18 are hingedly supported to studs 19 secured to the brake shell 12 while the other or upper ends are adapted to be expanded by hydraulic means, against the action of a spring 20, the opposite ends 85 of which are attached to the respective shoes, 90

said spring obviously serving to draw the brake shoes inward away from the brake drum 11.

21 represents a hydraulic cylinder that is adapted to be supplied with liquid through any suitable pipe connection, as for instance 22 as shown. The pistons within the cylinder are each provided with central aligned stems 23, the outer ends of which are seated 10 in yokes 24 that in turn are carried in recesses of the parallel spaced-apart flange portions 25 of the shoes. The hydraulic cylinder 21 and its operative connections with the shoes obviously serve to move the same upon the 15 pivots 19 and thereby expand their brake linings against the brake drum 11 and against the action of the before mentioned spring 20. The mechanism thus far described, and to which I have shown my invention applied, 20 is substantially in accord with present commercial practice, but is not dependent upon the successful operation of my invention, since the same is equally applicable to most 25 any form of brake lining, as used between cylindrical metal brake drums.

From the drawing, it will be seen that the shoes each have side flanges 25—25, that slideably engage angular-shaped guide plates 26 that are secured to the shell in a way to allow ample free radial movement of the shoe, but to hold it against sidewise movement, thus better to prevent rattling of the brake. The brake lining 27 for this style of 30 brake is secured to these expandable shoe members in a way to be moved into and out of contact with the brake drums 11 of the wheel, for the purpose of controlling the rotation of same.

The brake shoes, as is customary in this 40 type of brakes, include outer finished cylindrical surfaces, to which the brake linings 27 are secured as by means of rivets 28 and are thus adapted for engagement with the inner cylindrical surface of the brake drum, 45 through the application of hydraulic pressure, which causes the operation of the piston and outward movement of the shoes against the inner walls of the brake drum.

My improved signaling device for notifying 50 the driver or occupants of a car of the worn and defective condition of the brake, is connected with and made a part of the lining and consists in part in the use of a copper strip 29 of suitable shape and proportions, that is covered with an insulating material 30 and secured between the brake lining and the cylindrical walls 31 of the shoes, suitable openings 32 being provided in the insulative covered strips to accommodate 55 the rivets employed for securing the lining and metal strip to the shoe. There is one of these linings employed upon each shoe for engagement with the brake drum, and a wire 33 serves to connect each of these metal 60 strips through holes 34 in the shell, with a

binding post 35 secured to the face of the shell and from which a single wire 36 may be carried up to a lamp 37, a battery 38, and then grounded on the chassis.

From the construction and line of electric 70 connection described, it will be seen that with the use of the brake the lining will necessarily become worn and that continued use will cause it to wear through so that the drum which has worn through the lining will wear 75 away the insulation covering the copper strip, thereby exposing the same to direct contact with the drum, thus closing the circuit in a way to display the signaling lamp referred to and thus inform the driver of the dangerous condition of the brake. It will be obvious that where four-wheel brakes are employed, the wires 36 from the several pairs of brake shoes may be brought together in a suitable manner and from there connected by 80 a single wire to the lamp, etc. in substantially the manner shown in Fig. 2.

Having thus described my invention, what I claim and desire to secure by Letters Patent is:

1. In an automobile brake of the class described, the combination with a circular brake drum, a circular brake shoe, a flat circular lining intermediate of the drum and shoe, a metal strip positioned between the shoe and lining, an insulating covering enclosing the strip, a circuit wire connected to the strip and ground, and a battery and signal connected in circuit.

2. In an automobile brake of the class described, the combination with a circular brake drum, a circular brake shoe, a flat circular lining intermediate of the drum and shoe, of a metal strip covered with an insulating material positioned between the shoe and lining and having openings therethrough, rivets passing through the shoe, openings, and lining, a circuit wire connected to the strip and ground, and a battery and signal connected in circuit.

3. In an automobile brake of the class described, the combination with a circular brake drum, a circular brake shoe, a flat circular lining intermediate the drum and shoe, of a flat metal strip positioned between the shoe and lining, a covering of insulating material for said strip adapted to wear away with the wearing of the lining, rivets passing through and in spaced relation to the metal strip and secured to both the shoe and lining, a circuit wire connected to the metal strip and ground, and a battery and signal connected in circuit.

4. In an automobile brake of the class described, the combination with a circular brake drum, a brake shoe, a lining intermediate of the drum and shoe, a metal strip positioned between the shoe and lining and having a series of openings on each edge portion, a

covering of insulating material for said strip having openings that register with those of the metal strip, rivets passing through the openings, lining and shoe to secure the parts together, a circuit wire connected to the strip and ground, and a battery and signal connected in circuit.

Signed at Bridgeport, in the county of Fairfield and State of Connecticut, this 2nd 10 day of February, A. D. 1931.

ALFRED S. CATAUDELLA.
